(57) **CLAIM**

The ornamental design for a body for a fan/light combination, as shown and described.

DESCRIPTION

FIG. 1 is a bottom right side perspective view of a body for a fan/light combination showing my new design;

FIG. 2 is a top perspective view thereof;

FIG. 3 is a front elevation view thereof;

FIG. 4 is a side elevation view thereof, the opposite side being a mirror image of that shown;

FIG. 5 is a top plan view thereof; and,

FIG. 6 is a bottom plan view thereof.

The broken line showing of environmental structure in FIGS. 1-6 is for illustrative purposes only and forms no part of the claimed design.
